Attorney

UNITED STATES PATENT OFFICE.

CLARENCE H. CROWELL, OF FORT WORTH, TEXAS.

DISTRIBUTING APPARATUS FOR MATRICES OF TYPE-CASTING MACHINES AND THE LIKE.

Application filed January 7, 1924. Serial No. 684,791.

To all whom it may concern:

Be it known that I, CLARENCE H. CROWELL, a citizen of the United States, residing at Fort Worth, in the county of Tarrant and State of Texas, have invented certain new and useful Improvements in Distributing Apparatus for Matrices of Type-Casting Machines and the like, of which the following is a specification.

10 My invention relates to equipment for type-casting machines which employ character matrices for molding type bars and thereafter are elevated and distributed to the matrix magazines; and the object is to

15 provide means for elevating the matrices to and on the distributor bar without making use of the combination teeth which control the delivery of the matrices to the magazine channels. The advantage of such

20 equipment is that the combination teeth are not used and mutilated during transportation before they reach the distributor bar. Another object is to provide the elevating and transporting devices with selective

25 means for preventing the choking of the magazine channels with duplicate or other matrices. Other objects and advantages will be fully explained in the following description and the invention more particularly pointed out in the claims.

Reference is had to the accompanying drawings which form a part of this application.

Fig. 1 is a side elevation of a second elevator bar and distributor box bar. Fig. 2 is an end elevation of the same, showing a matrix applied thereto. Fig. 3 is an end elevation of a distributor box bar with the adjustable bar point applied thereto. Fig. 4 is a broken plan view of the distributor box bar with the adjustable bar point applied thereto. Fig. 5 is a broken plan view of the distributor box bar, showing the rectangular slot or cut-out for the adjustable bar point. Fig. 6 is an end elevation of the distributor box bar, showing the rectangular slot for adjustable bar point and showing the bar point in dotted outline and showing the relative position of the retaining screw. Fig. 7 is a side elevation of the bar point. Fig. 8 is an end elevation of the same.

Similar characters of reference are used

to indicate the same parts throughout the several views. 55

In the linotype art, means have been provided for elevating matrices and delivering the same to what is known in the art as a second elevator bar. The second elevator bar delivers the matrices to a distributor 60 box bar, and the distributor box bar delivers the matrices to the distributor bar which has channels or grooves in the sides which co-operate with the combination teeth of the matrices in assorting the matrices for the proper magazine channels. The former construction of the second elevator bar and the distributor box bar with the channels on the sides effected rapid wear of the matrices and the matrices were soon rendered 65 worthless and new matrices had to be prepared. I have provided improvements in the second elevator bar and in the distributor box bar which will avoid the wear on the combination teeth of the matrices so that 70 the life of the matrices is prolonged. 75

The improved second elevator bar 1 is provided with the usual means on the upper part thereof for mounting the bar on the machine. The bar 1 has smooth inclined 80 sides 2 instead of channeled sides as heretofore made. The bar 1 is provided with means for supporting the matrices as they are moved along towards the distributor box bar. The inclined sides 2 extend down 85 to a flat strip or shank portion 3 and a bead 4 is formed on the bottom of the shank portion 3 and the bead 4 is approximately cylindrical in form. The distributor box 90 bar 5 is provided with similar sides 2, shank portion 3, and bead 4.

Improved matrices 7 are provided with approximately cylindrical openings 6 which are connected by restricted portions for making connection with the usual V-shaped 95 openings which are provided with the combination. The opening 6 will take the friction and support off of the combination teeth of the matrices. The matrices will be pushed along on the beads 4. On operation, after the type bar is cast, the matrices and space bands (not shown) are elevated by the first elevator (not shown) to the second elevator and are forced from the first elevator on the second elevator bar 1 into engagement 100 with the bead 4. The second elevator 105

is then raised for delivering the matrices to the distributor box bar 5 and the matrices are moved to the bar 5 by the usual pusher. The corresponding parts of bar 5 are similar to the parts 2, 3, and 4 of bar 1.

The matrices are moved by the pusher (not shown) to the distributor bar which forms no part of the improvements herein. The space bands may be provided with the 10 same openings 6 and be handled in the same manner as the matrices until they are delivered to the space band box. The distributor box bar is provided with an adjustable bar point 8 for proper selection of the matrices so that only one matrix can pass at a time. The bar point 8 enters a groove 9 in the thicker matrices as each matrix is to be delivered to the distributor bar and in case 15 of matrices too thin for a groove 9, only 20 one matrix can pass at a time because the bar point 8 projects so far that only thin matrix can pass.

The different bars herein mentioned are all transfer bars and are used for handling 25 matrices. The distributor box bar 5 and the second elevator bar 1, having smooth inclines and the beads 4, prevent the hammering and mutilating of the combination teeth of the matrices and thus effect a saving in 30 matrices as well as making the handling or moving of the matrices more easily accomplished and more accurately distributed.

The improved bar point 8 is adjustably mounted in the end of the distributor box 35 bar 5. The bar 5 has a rectangular recess

10 in the end and the bar 8 has a shank 11 has a portion thereof approximately square in cross-section which projects into the recess 10. A screw 12 is screwed down through the upper part of the bar 5 and 40 clamps the shank 11 in the recess 10. The shank 11 can be projected more or less into the recess 10 and be clamped at any point of adjustment.

As a part of the distributing mechanism 45 of this invention, matrices of special make are necessary. Such matrix is shown in Fig. 2 and is provided with an approximately cylindrical opening 6 which is adapted to engage the beads 4 so that all the matrices 50 can be moved along on the beads 4 when the matrices are to be restored to the matrix magazines.

What I claim, is,—

1. In a type-casting machine provided 55 with a distributor box bar having a socket therein; an adjustable bar point having a shank projected into said socket and a screw for clamping said shank in said socket.
2. In a type-casting machine provided 60 with a distributor box bar having a socket therein; an adjustable bar point having a shank projected into said socket, said shank being relatively thicker than the bar point, and a screw for clamping said shank in said 65 socket.

In testimony whereof, I set my hand, this 2nd day of January, 1924.

CLARENCE H. CROWELL.
